LOADING DEVICE

William F. Borgerd, Evansville, Ind., assignor to
 International Harvester Company, a corporation of New Jersey

Application October 15, 1951, Serial No. 251,379

3 Claims. (Cl. 214—130)

1

This invention relates generally to a loading device and more particularly to a device for lifting a motor-compressor assembly from an air-conditioning unit.

Many refrigeration systems are being equipped with an electric motor and compressor fashioned as one integral unit and hermetically sealed in a common casing. In the larger capacity refrigeration systems, such as employed in an air-conditioning unit for a home, the motor-compressor assembly is usually of such size and weight that it is difficult for one person to remove the assembly from the unit. When servicing of the motor-compressor assembly is needed, it is generally necessary to remove the motor-compressor from the casing and take it to a suitable shop for repairs. If the assembly is too heavy for one man to lift from the unit, the services of two men will be required for the job, thus causing servicing of the unit to be difficult and costly. The purpose of the present invention is to provide a loading device which will overcome these difficulties.

One object of the present invention is to provide a loading device which facilitates the removal of a heavy piece of machinery from a casing.

Another object of the present invention is to provide a loading fork which enables one person to lift a motor-compressor assembly from the casing of an air-conditioning unit.

Another object of the present invention is to provide a horizontal bar rigidly fixed to the casing upon which the fork is adapted to be rested and pivoted thereabout.

Another object of the present invention is to provide the motor-compressor assembly with two spaced apart brackets having axially aligned apertures therethrough into which a pin is adapted to be positioned so that a hooked portion of the loading fork engages the pin for raising the assembly from the unit.

Another object of the present invention is to provide a collar adapted to be fastened over the top of the motor-compressor assembly and which is provided with a link for engaging the loading fork.

Another object of the invention is to provide the loading fork with an elongated portion along which the motor-compressor assembly can be slid after it has been lifted from the casing.

The invention, together with the above and other objects and advantages thereof, will be more fully understood from the following description taken in connection with the accom-

2

panying drawings forming a part of this specification, and of which:

Fig. 1 is a side vertical section of an air-conditioning unit embodying the invention.

Fig. 2 is a horizontal sectional view taken along line 2—2 of Fig. 1 with the loading fork inserted into the unit.

Fig. 3 is a top plan view of the collar and loading link before it is fastened to the motor-compressor assembly.

Fig. 4 is a front elevational view of the support bar.

Fig. 5 is a vertical sectional view of a portion of the unit showing the motor-compressor assembly in readiness for removal from the unit.

Fig. 6 is a vertical sectional view of a portion of the unit after the motor-compressor unit has been raised from the unit by the loading fork.

Referring to the drawings for a detailed description of the invention, an air-conditioning unit 10 is shown secured to the outer surface of a building wall 11. An opening 12 is provided in the wall 11 and a removable door 13 is adapted to close the opening. Unit 10 comprises a housing 14 having a frame 15, bottom wall 16, rear wall 17, front wall 18, top wall 19, and end walls 20 and 21. The frame 15 comprises channel members 22, 23, 24, and 25 which are joined together in any suitable manner such as by welding. Front wall 18 is secured to top wall 19 and channel 23 by screws 26 in order that it can be easily removed when desired. End walls 20 and 21 are each provided with an opening therethrough with screens 28 and 29 secured therein for the purpose of preventing foreign objects from entering the casing 14. Three brackets 30 are secured to channel 25 with a lower leg of each fastened to wall 11 by a bolt 31 and nut 32. The upper portion of rear wall 17 is fastened to wall 11 by several bolts 33 and nuts 34.

Secured within casing 14 is a refrigerant condenser 35 and an electric motor 36 having a fan 37 connected thereto which draws outside air through screen 28 and expels it through screen 29 when the electric motor is operating. A plate 38, having downturned edge portions 39 and 40, is secured to bottom wall 16 in any suitable manner, as by welding the edge portions thereto. Mounted upon plate 38 is motor-compressor assembly 41 having several bolts 42 secured to the lower end, each bolt being provided with a resilient pad 43 upon which the assembly rests. Plate 38 is provided with spaced apart holes 44 through which the bolts 42 extend and nuts 45

are threaded onto the bolts to secure the assembly 41 to the plate.

The motor-compressor assembly 41 comprises an electric motor and a compressor hermetically sealed within a casing having a refrigerant inlet 46 and outlet 47. The outlet 47 is connected to one end of conduit 48 by joint 49 and the other end of the conduit is connected to the inlet of condenser 35. The outlet of the condenser 35 is connected to conduit 50 which extends through an opening 52 above door 13 into the building. A refrigerant evaporator, not shown, may be positioned inside the building with conduit 50 connected thereto. The evaporator outlet is connected to conduit 51 which extends through opening 52 and is joined to the motor-compressor inlet 46 by joint 53. During the refrigeration cycle, compressed refrigerant is forwarded from motor-compressor assembly 41 by conduit 48 to condenser 35 where it is cooled and condensed by outside air being circulated by fan 37. The condensed refrigerant is then conveyed by conduit 50, through the evaporator, and then returned to the motor-compressor 41 by conduit 51. By circulating room air into contact with the evaporator, the building will be cooled to a desired temperature.

Rigidly fastened to the channel 23 is a support bar 54 having downturned end portions 55 and 56 which are welded to the inturned leg of the channel 23. Two spaced apart brackets 57 are secured to the outer casing of the motor-compressor assembly 41, preferably below the center of gravity of the assembly. Each bracket is provided with a curved portion 58, which fits against the casing, and an outwardly extending leg 59 which is provided with an aperture 60 therethrough.

During normal operation of the refrigeration system, front cover 18 is held securely in position by screws 26. When servicing of the unit is required, the screws 26 are removed and the cover 18 is detached from the unit 10 in order to provide access into housing 14. As mentioned heretofore, a motor-compressor assembly of sufficient size to condition the air of a residential building will be quite heavy and it will be difficult for one person to remove or replace the assembly. In the present invention, a loading fork 61 is provided to enable one person to remove or replace the assembly. The fork 61 comprises two longitudinally extending handle portions 62 and 63 which are held in spaced relationship by transverse members or braces 64 and 65. One end of longitudinal portion 62 is provided with an upturned hook portion 66 and the corresponding end of longitudinal portion 63 is provided with an identical upturned hook portion 67. Secured to the lower edge of each horizontal portion is a triangular shaped support 68 having two upstanding legs 69 and 70 which are connected by a web portion 71. The web portion 71 is provided with a semi-circular recessed portion or groove 72 which is adapted to fit over support bar 54.

After front cover 18 is removed, a cross pin 73 is slipped through apertures 60 of brackets 57. Loading fork 61 is then inserted into the casing 14 with the grooves 72 of supports 68 resting upon support bar 54 and the hooked portions 66 and 67 engaging cross pin 73 as shown in Fig. 2. Next a collar 74 is slipped over the upper end of the motor-compressor assembly 41 and is secured thereto by tightening the nut 75 of clamp bolt 76. As best seen in Fig. 3, the end portions 77 and 78 of the collar 74 are bent at an angle thereto and

are provided with apertures 79 and 80 therethrough which slidably receive a cross pin 81. A U-shaped loading link 82, having looped end portions 83 and 84 with apertures therethrough, is joined to the collar 74 by cross pin 81 after the link has been slipped around the longitudinal portions 62 and 63 of the loading fork 61. The parts are now connected in the manner best shown in Fig. 5 of the drawing. Nuts 45 are removed from bolts 42, and the compressor's inlet 46 and outlet 47 are disconnected from conduits 51 and 48 by breaking joints 53 and 49 so that the motor-compressor assembly 41 is free to be removed from the casing 14.

In the illustrated embodiment, an automobile truck body floor is represented by reference numeral 85 and it is contemplated that the truck be backed in close to the casing 14. The person who is removing the assembly 41 may grasp the outer ends of longitudinal portions 62 and 63 of the loading fork 61 and bear downwardly toward the truck floor 85. The fork 61 will rotate about support rod 54 and the assembly will be lifted by hook portions 66 and 67. Since the distance from support bar 54 to the hooked portions is small compared with the distance from the support bar to the outer ends of longitudinal portions 62 and 63, the fork 61 will act as a lever and enable one person to lift a motor-compressor assembly of great weight. As the fork 61 is rotated about the support bar 54, loading link 82 will hold the top portion of the assembly 41 at a fixed distance from the fork until the center of gravity of the assembly has been moved to the left of cross pin 73, whereupon the assembly will rotate about the pin to the position shown in Fig. 6. After rotating the fork to a position with the longitudinal portions 62 and 63 resting upon the truck bed 85, loading link 82 is removed from pin 81 and the assembly 41 is slid along the fork into the truck bed. The longitudinal portions 62 and 63 are spaced so that the circular shaped casing of the assembly 41 will fit partially therebetween and will be held in position as the assembly is pulled therealong.

As can be seen from the foregoing, the loading device enables one person to easily remove the assembly 41 from the casing 14. It is also apparent that the assembly could also be replaced in the casing by reversing the procedural steps. In the illustrated embodiment, the assembly is shown being loaded onto a truck bed but it is to be understood that it could be loaded into any other container. The described loading device enables one person to easily and quickly remove or replace a heavy motor-compressor assembly from a casing. The invention has been described in connection with an air-conditioning unit merely for purposes of illustration and it is to be understood that it could be used for handling a heavy object or piece of machinery.

It will be apparent to those skilled in the art that other changes could be made in the form of the apparatus disclosed without departing from the spirit of the invention as set forth in the appended claims. Having now described the invention, what is claimed is as follows:

1. In a loading device for removing and replacing a vertically elongated casing having a cylindrical contour, a pair of straight longitudinal members, said members disposed in a parallel spaced-apart relationship some distance less than the diameter of said casing, brace means for maintaining said members in said parallel spaced-apart relationship so that said casing is slidably

along said members when the longitudinal axis of said casing is parallel to said members, an upturned flange on one end of each of said members, fulcrum means mounted to depend from said members substantially closer to the end of each of said members having said flange thereon than to the other end of each of said members for permitting a leverage action of said members about said fulcrum means, a pin engageable with a portion of said casing below the center of gravity thereof, said pin positionable on the upper surface of each of said members in cooperation with each of said flanges so that when a leverage action is applied to said members said pin is pivoted and said casing is raised, a circular strap positionable about said casing above the center of gravity thereof, a U-shaped link positioned about said members between said fulcrum means and said other end of said members and pivotally mounted to said strap so that the upper end of said casing is pivotable about said pin toward said members only.

2. In a loading device for removing and replacing a vertically elongated casing having a cylindrical contour, a pair of straight longitudinal members, said members disposed in a parallel spaced-apart relationship some distance less than the diameter of said casing, brace means for maintaining said members in said parallel spaced-apart relationship so that said casing is slideable along said members when the longitudinal axis of said casing is parallel to said members, an upturned flange on one end of each of said members, fulcrum means comprising two pairs of legs, the upper ends of each of said pair of legs mounted in a spaced-apart relationship to depend from one of said members substantially closer to the end of each of said members having said flange thereon than to the other end of each of said members, the lower ends of each of said pair of legs joined to a web having a concave bearing surface on the underside thereof, whereby said bearing surfaces are positionable upon a convex bearing surface to permit a leverage action of said members, a pin engageable with a portion of said casing below the center of gravity thereof, said pin positionable on the upper surface of each of said members in cooperation with each of said flanges so that when a leverage action is applied to said members said pin is pivoted and said casing is raised, a circular strap positionable about said casing above the center of gravity thereof, a U-shaped link positioned about said members be-

tween said fulcrum means and said other end of said members and pivotally mounted to said strap so that the upper end of said casing is pivotable about said pin toward said members only.

3. In a loading device for removing and replacing a vertically elongated casing having a cylindrical contour, a pair of straight longitudinal members, said members disposed in a parallel spaced-apart relationship some distance less than the diameter of said casing, a pair of braces mounted between said members for maintaining said members in said parallel spaced-apart relationship so that said casing is slideable along said members when the longitudinal axis of said casing is parallel to said members, an upturned flange on one end of each of said members, fulcrum means consisting of two pairs of legs, the upper ends of each of said pair of legs mounted in a spaced-apart relationship to depend from one of said members substantially closer to the ends of said members having the flanges thereon than to the other ends of said members, the lower ends of each of said pair of legs joined to a web having a concave bearing surface on the under side thereof, a bearing element positionable adjacent said casing, said bearing element having a convex surface upon the upper side thereof, said concave bearing surface of said web engageable with said convex surface of said bearing element whereby a leverage action of said members is permitted, a pin engageable with a portion of said casing below the center of gravity thereof, said pin positionable on the upper surface of each of said members in cooperation with each of said flanges so that when a leverage action is applied to said members said pin is pivoted and said casing is raised, a circular strap positionable about said casing above the center of gravity thereof, a U-shaped link positioned about said members between said fulcrum means and said other end of said members and pivotally mounted to said strap so that the upper end of said casing is pivotable about said pin toward said members only.
